Attorney

UNITED STATES PATENT OFFICE.

AUGUST P. FROMMER, OF CLEVELAND, OHIO.

FUEL-SAVING DEVICE FOR CARBURETORS.

Application filed August 18, 1924. Serial No. 732,644.

The objects of the invention are to provide automatically acting means for supplying the explosive mixture of an explosion engine with an added charge of moist air, and an added charge of dry air, and also providing means for accumulating the excess of gasoline in the charge that has been imperfectly commingled therewith, as when the carburetor has been flushed, and commingling the same with a mixture of dry air and moist air.

The invention is embodied in a device which is interposed between the adjacent flanges of the carburetor outlet pipe and of the intake pipe leading to the cylinder or cylinders, and which is provided with a passage for hot moist air leading preferably from the radiator of the car thereto, and a passage for dry air, both passages communicating with the intake passage of the engine.

The invention is illustrated in the accompanying drawings, hereinafter described and specifically pointed out in the claims.

The device is possessed of many advantages, among which may be enumerated an increased amount of power produced by the action of the moisture which tends to lubricate the engine parts and to prevent the deposit of carbon thereon. It also tends to make the action of the engine smooth and quiet. Also since the excess of fuel oil is deflected or withdrawn from the charge, a more perfect mixture and more perfect combustion is produced. Also since the excess of fuel oil is drained away from the charge and is afterwards reintroduced therein, the device will avail to utilize all the fuel and eliminate waste.

It includes a chamber for the deposit of fuel oil and a passage through which an excess of fuel oil leads to said chamber, and from which it may be drawn, commingled with a supply of hot moist air and of dry air, thus enriching the charge as well as supplying moisture to the same.

In the drawings, Fig. 1 is a side elevation of the engine of a motor car, showing the location of the device, and its connection with the carburetor and intake pipe or manifold of the car, and also its connection with the radiator; Fig. 2 is a vertical transverse section thereof on line 1—1 Fig. 3; Fig. 3 is an edge elevation thereof.

In these drawings, A represents the carburetor, B represents the manifold, C represents the combined moisture and dry air

supplying the fuel oil salvaging device, D represents the source, such as the radiator, from which hot, moist air may be supplied to the device, E represents a tube for supplying moist air to a chamber F in the body of the device, through the orifice G. H is a second chamber in this body into which dry air enters through the orifice I, and separated from the chamber F by a partition F'. J is a bent tube, the extremities K, K of which enter these chambers and through the upper openings L, L in which moist and dry air are thrown by engine suction into the manifold.

On the bottom of the passage S in this device, which is a continuation of the intake passage C, a baffle N is elevated to extend into the passage C, and check the passage of any waste fuel oil or excessive amount thereof in the charge, which is then drawn through the opening O adjacent to the bottom of the passage and preferably into the dry air passage in the tube K, and is commingled with the additional supply of hot, moist and dry air drawn through the sides K, K of the tube F, into the intake pipe through the opening P in the partition separating the chambers F and H, thus utilizing and consuming all the fuel oil without waste, and preventing the production of an over-rich mixture. A closure Q in the air admission tube above the opening O prevents suction from drawing the air and waste fuel oil directly into the intake passage, but requires it to be mixed with hot moist air and with an additional supply of dry air, thus making a more perfect mixture before entering this passage.

By the use of this device the tendency of car drivers to speed up and use too rich a mixture is corrected.

Having described the invention, what I claim as new and desire to secure by Letters Patent is:

1. In a device of the character described, a section or member inserted in the intake passage of an explosion engine, said member containing a continuation of said passage, chambers therein communicating with said intake passage, a pipe leading to one of said chambers from a source of hot moist air, the other chamber being provided with an air inlet opening, said interposed member extending upward partially across said intake passage, and a discharge opening for waste fuel oil in said passage leading from

one side of said interposed member to one of said chambers therein.

2. In a device of the character described, a section or member inserted in the intake 5 passage of an explosion engine, said member containing a continuation of said passage, chambers therein communicating with said intake passage, a pipe leading to one of said chambers from a source of hot moist 10 air, the other chamber being provided with an air inlet opening, said interposed member extending upward partially across said

intake passage, and a discharge opening for waste fuel oil in said passage leading from one side of said interposed member to one of said chambers therein, and a V-shaped pipe having its extremities inserted in said chambers and projecting into said intake passage, said projecting portion being provided with a suction opening. 15 20

In testimony whereof, I hereunto set my hand this 16th day of August, 1924.

AUGUST P. FROMMER.
